UNITED STATES PATENT OFFICE

157,498

PERFUME CONTAINER

Howard Kestenbaum, Great Neck, N. Y.

Application March 24, 1949, Serial No. 1,597

Term of patent 14 years

(Cl. D58—6)

To all whom it may concern:

Be it known that I, Howard Kestenbaum, a citizen of the United States and a resident of Great Neck, Long Island, New York, have invented a new, original, and ornamental Design for a Perfume Container, of which the following is a specification, reference being had to the accompanying drawing forming part thereof, in which:

Fig. 1 is an exploded elevational view of a perfume container, embodying my new design;

Fig. 2 is a plan view looking upward of the cap of the same; and

Fig. 3 is a plan view looking upward of the base of the perfume container.

I claim:

The ornamental design for a perfume container, as shown.

HOWARD KESTENBAUM.
